Primary Examiner — Mitchell Siegel(74) *Attorney, Agent, or Firm* — Fish & Richardson P.C.(57) **CLAIM**

The ornamental design of a thread aspirating device for a circular knitting machine, substantially as shown and described.

DESCRIPTION

FIG. 1 is a perspective view of a thread aspirating device for a circular knitting machine in accordance with the present design;

FIG. 2 is a top view thereof;

FIG. 3 is a left side view thereof;

FIG. 4 is a bottom view thereof;

FIG. 5 is a right side view thereof;

FIG. 6 is a rear side view thereof; and,

FIG. 7 is a front side view thereof.

Generally, the invention pertains to an ornamental design for an article of manufacture. The article is not limited to the scale shown herein.

The broken line portions of the figures are included to show unclaimed subject matter only and form no part of the claimed design.
